SIGNALING ON RAILWAYS

APPLICATION FILED AUG. 9, 1903.

2 SHEETS—SHEET 2

Diagram illustrating a mechanical system. A central vertical column is shown with a pulley system at the top, consisting of two pulleys and a string. A weight m hangs from the left pulley, and another weight m hangs from the right pulley. The vertical column is connected to a horizontal beam. The horizontal beam has a spring w attached to its left end and a mass w attached to its right end. The entire system is supported by a base, which also contains a spring w .

UNITED STATES PATENT OFFICE.

CHARLES MARK JACOBS AND ROBERT JAMES INSELL, OF READING, AND ERNEST ALBERT BENNETT BOWDEN, OF HANWELL, ENGLAND.

SIGNALING ON RAILWAYS.

No. 883,026.

Specification of Letters Patent.

Patented March 24, 1908.

Application filed August 9, 1907. Serial No 387,859.

To all whom it may concern:

Be it known that we, CHARLES MARK JACOBS, ROBERT JAMES INSELL, and ERNEST ALBERT BENNETT BOWDEN, all subjects of the King of Great Britain, residing, respectively, at St. Cuthberts, Alexandra Road, Reading, in the county of Berks, England, telegraph engineer; 17 Russell street, Reading, in the county of Berks, England, signal engineer, and 21 Balfour avenue, Hanwell, in the county of Middlesex, England, traffic officer, have jointly invented certain new and useful Improvements in Signaling on Railways, of which the following is a specification.

15 In an installation for signaling on railways wherein a single ramp on the line at each signaling position invariably raises a lever carried by the train to open a normally closed circuit on the latter, and at the same time

20 serves together with the said lever as part of a normally open electric circuit which may be closed by the signalman. The effect of opening the normally closed circuit is to de-

25 energize an electromagnet to release a lever that operates a danger signal, and the effect of closing the normally open circuit is to maintain the said electromagnet energized and thus to restrain the danger signal; at the same time a safety signal included in this cir-

30 cuit is operated.

The present invention relates to improvements in such an installation, whereby the normally closed electric circuit is eliminated. For this purpose the mechanism that operates the danger signal is mechanically released when the ramp raises the lever carried by the train or a substitute for that lever such as a rod. For instance the raising of the lever may withdraw a catch that releases the mechanism, thus causing the danger signal to be given unless the said mechanism is restrained by some means such as through the energizing of an electro magnet by the closing of the normally open circuit referred to

45 above.

A suitable construction is illustrated in the accompanying drawings, in which

Figure 1 is a diagrammatic front part elevation of the mechanical portion of the signaling apparatus on the locomotive, Fig. 2 is a part sectional elevation on line 2-2 of Fig. 1, also showing a local electrical circuit situated on the engine, Fig. 3 is a part plan and Fig. 4 is a diagrammatic representation of a second or ramp circuit.

The whistle *a* is normally kept closed by a lever *b*, on an inclined surface of which bears a cam *c* fixed on a disk *d* mounted free to turn on a spindle *e*. Also free to turn on this spindle is a drum *f* within which is fixed so as to turn therewith an electromagnet *g* with its pivoted armature *g'*.

The drum carries sprocket teeth *f'* engaging with which is a chain *h* having one end attached to a weight *i* and the other to a steel wire *h'* which extends through a brass tube *h''* and is connected at its other end with the arm *k'* of the lever *k* by means of an insulated washer *h'''*. The lever *k* is adapted to be operated by a ramp *u* that is fixed between the rails and carries an insulated conductor *u'*.

The free end *g''* of the armature *g'* extends through a port *f''* in the face of the drum *f* into a slot *d'* in the disk *d*, the walls of the slot being notched or shouldered. The terminals of the electromagnet *g* are connected by leads *l* respectively with insulated contacts *m* on the periphery of the drum *f*. Brushes *n* bear respectively on these contacts, one being connected by lead *o* with one terminal of a winding *p* on a polarized relay carried by the engine, and which is employed for establishing a local or holding-on circuit, hereinafter referred to, when the magnet *g* is energized by the closing of the normally open circuit; the other end of said winding is connected by lead *o'* with earth, say through the mass of the locomotive and the running rails, while the other brush *n* is connected by lead *o''* with lever *k* which is mounted in insulated manner on the under-frame of the locomotive.

The second winding *p'* of the polarized relay is connected to the bell *q* to be used as a safety signal when no danger signal is to be given, and the battery *r* carried by the engine. When the relay is energized by the line battery *w* a holding on circuit including a local battery *r*, coil *p'*, working stop *t'*, tongue *t* and switch *s* is established by the engagement of the tongue *t* of the relay with the working stop *t'* as in Fig. 2, thereby causing the bell *q* to sound by the closing of the ringing circuit through battery *r*, bell *q*, working stop *t'*, tongue *t* and switch *s* until the driver breaks the local or ringing circuit by pressing the push button or switch *s*.

When the locomotive passes over a ramp, the lever *k* is raised, whereby the wire *h'* is pulled, weight *i* raised by the ramp and drum

f rotated clockwise. In the normal position of the parts the end *g*² of the armature rests in the right hand half of the slot *d'*, so that as it turns with the drum it engages with the 5 end *d*² of the notched part of the slot and causes the disk to turn with the drum. Thus the cam *c* rides off the inclined surface of the lever *b* the free end of which rises and the whistle sounds. When the locomotive has 10 passed over the ramp, the lever *k*, wire *h*, weight *i* and drum *f* return to their normal positions. The disk *d*, however, remains in the position into which it has been turned until the engine-driver lifts the lever *e'* which 15 is free to turn on spindle *e*, so as to engage a stop *d*³ on the disk and force the latter back into the normal position causing the cam *c* to engage the lever *b* which in turn closes the whistle.

20 If the line is clear and no danger signal is to be given, the signalman before the approach of a train turns a switch *v* to close a circuit from a battery *w* situated beside the track through the conductor *w'* on the ramp, 25 the lever *k*, lead *o*², one contact *m*, the magnet *g*, the other contact *m*, lead *o*, winding *p* and through the locomotive and running rails to earth, as represented in Fig. 4. The magnet *g* is thus energized and raises its armature *g'* so that the end *g*² thereof rests in the left hand part of slot *d'*. Thus, when the drum *f* is rotated the end *g*² of the armature clears the notch in the slot and merely rides in the left hand half of slot *d'* and the disk *d* 35 is not then turned so that the whistle remains closed. At the same time as the magnet *g* is energized and the danger signal restrained, the polarized relay circuit is established and causes the safety bell *q* to sound 40 until this circuit is broken by the driver pressing the push *s*.

Having thus described the nature of this invention and the best means we know of carrying the same into practical effect, we 45 claim:—

1. In an installation for signaling on rail-ways, a ramp on the track, a mechanical device carried by the train and adapted to be operated by the ramp, a danger signal on the 50 train adapted to be operated positively while the said mechanical device is being actuated by the ramp, a normally open electric

circuit in part carried by the train and in part by the ramp, an electromagnetic device on the train situated in the said normally open 55 electric circuit and adapted, when energized, to restrain the said danger signal, and means outside the track for closing the said normally open circuit.

2. In an installation for signaling on rail-ways, a ramp on the track, a lever carried by the train and adapted to be raised by contact with the said ramp, a danger signal on the train, a mechanical connection between the said lever and the said signal whereby the 65 latter is operated when the lever is raised, a normally open electric circuit in part carried by the train and in part by the ramp, an electromagnetic device on the train situated in the said normally open electric circuit and adapt- 70 ed when energized to restrain the said danger signal, and means outside the track for clos- ing the said normally open circuit.

3. In an installation for signaling on rail-ways, a ramp on the track, a lever carried by 75 the train and adapted to be raised by contact with the said ramp, a whistle on the train, a valve controlling the said whistle, a lever controlling the said valve, a disk adapted to turn on its axis, a cam fixed on the said disk 80 and adapted to engage the said valve controlling lever, a drum free to turn on its axis, an electromagnet mounted within the said drum and adapted to turn therewith, a piv- 85 oted armature to the said electromagnet 90 adapted to extend through a slot in the said disk, means connecting the said drum with the said lever that comes in contact with the said ramp, the said means being adapted to turn the drum when the lever is raised, a nor- 95 mally open electric circuit in part carried by the train and in part by the said ramp, the said circuit including the said electromagnet, and means outside the track for closing the said normally open circuit.

In testimony whereof we have signed our names to this specification in the presence of two subscribing witnesses.
